LEVI L. TOWER, OF SOMERVILLE, MASSACHUSETTS.

Design No. 4,291, dated August 9, 1870.

DESIGN FOR AN INKSTAND.

The Schedule referred to in these Letters Patent and making part of the same.

To all persons to whom these presents may come;

Be it known that I, LEVI L. Tower, of Somerville, in the county of Middlesex and State of Massachusetts, have invented or produced a new and useful Design for an Ink or Mucilage-Stand; and I do hereby declare the same to be fully described in the following specification, and represented in the accompanying drawing, of which--

Figure 1 denotes a side elevation of an ink or mucilage-stand, as constructed in accordance with my invention;

In the said drawing—

A denotes the base of the ink or mucilage-stand, which may be either circular or polygonal in horizontal section, such part being hollow and constituting the ink-reservoir.

Surmounting the said base is a hollow dome, B, which is of a bell-shape, and intended to represent a bee-hive, made of parallel or spirally-wound bands of straw, or, if desirable, the said dome may be smooth on its outer surface.

In front of the said dome, and opening out of the ink-reservoir or base, is the dip-fountain C, whose mouth is of a circular form and extends a short distance above the top of the base.

D is a niche or recess formed in the front face of the dome, the base of the niche resting on the top of the dip-fountain, and being curved to an arc of a circle corresponding with the interior curvature of the dip-fountain.

Having described the shape or configuration of my said invention,

What I claim is as follows:

The said design for an ink or mucilage-stand, substantially as described and represented.
